UNITED STATES PATENT OFFICE.

ELMER P. GOLDSMITH, OF NEWARK, NEW JERSEY, ASSIGNOR TO MILLER & GOLDSMITH, OF NEW YORK, N. Y., A FIRM CONSISTING OF WILLIAM G. MILLER AND ELMER P. GOLDSMITH.

DESIGN FOR A NOVELTY HOLDER FOR SOILED OR CLEAN HANDKERCHIEFS.

Application filed November 13, 1925. Serial No. 15,415. Term of patent 3½ years.

To all whom it may concern:

Be it known that I, ELMER P. GOLDSMITH, a citizen of the United States, residing in Newark, in the county of Essex and State of New Jersey, have invented a certain new, original, and ornamental Design for Novelty Holders for Soiled or Clean Handkerchiefs, of which the following is a specification, reference being had to the accompanying drawings, of which—

Figure 1 is a front elevation; Fig. 2 is a side elevation, and Fig. 3 is a rear elevation of a novelty holder for soiled or clean handkerchiefs showing my new design.

I claim:

The ornamental design for a novelty holder for soiled or clean handkerchiefs as shown.

ELMER P. GOLDSMITH.
